Patented Feb. 10, 1914.

2 SHEETS—SHEET 2.

UNITED STATES PATENT OFFICE.

ORVILLE NELL, OF BRIDGEPORT, ILLINOIS.

AUTOMATIC LOCK FOR RAILWAY-SWITCHES.

1,087,046.

Specification of Letters Patent.

Patented Feb. 10, 1914.

Application filed June 2, 1913. Serial No. 771,355.

To all whom it may concern:

Be it known that I, ORVILLE NELL, a citizen of the United States, residing at Bridgeport, in the county of Lawrence and State 5 of Illinois, have invented certain new and useful Improvements in Automatic Locks for Railway-Switches; and I do declare the following to be a full, clear, and exact description of the invention, such as will enable others skilled in the art to which it 10 pertains to make and use the same.

This invention relates to improvements in automatic locks for railway switches.

One object of the invention is to provide 15 a lock adapted to automatically engage and lock the point of a switch rail when brought to a closed position.

Another object is to provide a switch lock 20 of this character having means whereby the same is released by the movement of the switch operating mechanism when actuated to open the switch.

With these and other objects in view, the 25 invention consists of certain novel features of construction, and the combination and arrangement of parts as will be more fully described and claimed.

In the accompanying drawings: Figure 1 30 is a plan view of a railway track and switch showing the application of my improved lock and illustrating the switch in closed position; Fig. 2 is a vertical cross sectional view thereof taken on the line 2—2 of Fig. 1; Fig. 3 is a similar view taken on the line 33 3—3 of Fig. 1; Figs. 4 and 5 are views similar to Figs. 2 and 3 taken respectively on the same lines and illustrating the position of the parts when the lock is released and the switch open; Fig. 6 is a detail vertical longitudinal section taken on the line 6—6 of Fig. 5.

Referring more particularly to the drawings, 1 denotes the main track rails and 2 denotes the side track rails to which my 45 improved lock is applied.

3 and 4 denote the movable switch points which are connected by the usual or any suitable switch shifting bar 5, said bar being here shown as secured to the lower sides of 50 the switch points by suitable clips and as projecting a suitable distance beyond one side of the tracks.

Arranged alongside the tracks is a switch stand 6 in which is arranged any suitable 55 form of switch operating mechanism, said switch operating mechanism being here

shown as comprising a vertically disposed shaft 7 which is revolubly mounted in the casing of the stand and projects above the same. On the upper end of the shaft is a 60 bracket 8 of any suitable form, while fixed to the shaft within the stand 6 is a disk 9 having thereon a segmental gear 10 with which is engaged a pinion 11 fixed on the inner end of a switch throwing shaft 12 65 journaled in one side of the switch stand and having fixed on its outer end a switch throwing lever 13. The lever 13 when swung in one direction for closing the switch is brought into engagement with a keeper 14 70 and when swung in the opposite direction for opening the switch is brought into engagement with a keeper 15. The keepers 14 and 15 may be provided with any suitable locking mechanism whereby the switch 75 throwing lever is locked in position for holding the switch closed or open.

The parts described in the foregoing may be of the usual or any suitable construction 80 and do not form a part of the present invention which comprises means for positively locking the switch in a closed position and which consists of a locking bar 16 hinged to and supported at its outer end in a bracket 17 secured to two of the ties adjacent to the 85 outer side of the track rails as shown. In the upper side of the locking bar 16 is formed a locking notch 18 the length of which is sufficient to receive the main track rail and the switch point 3 when the latter 90 is closed or brought into engagement with the rail as is clearly shown in Figs. 2 and 4 of the drawings. The inner end of the locking bar 16 is loosely engaged with a vertically disposed guide rod 19 the lower end of 95 which is secured in the roadbed of the railway in any suitable manner and the upper end of which is secured in a stop plate 20 arranged across and having its ends secured to two of the ties as shown. Arranged on 100 the guide bar 19 below the end of the locking bar 16 is a coiled spring 21 the pressure of which is applied to yieldingly force and hold the locking bar 16 upwardly and in operative engagement with the rail and 105 switch point 3 whereby when the switch point is brought to a closed position or in engagement with the rail 1, the bar 16 will be swung upwardly by the spring and the notch 18 therein engaged with the rail and 110 switch tongue.

In order to disengage the notch 18 from

the rail and switch point to release the latter, I provide a releasing mechanism comprising a short arm 22 which is secured to the lower side of the free end of the bar 5 and projects laterally therefrom and beneath the switch shifting bar 5. The arm 22 has revolubly mounted on its outer end a sleeve or roller 23. Engaged with the lower side of the switch shifting bar 5 and 10 having a limited sliding engagement thereon is a trip bar 24 which corresponds substantially to the length and width of the bar 5 and is engaged with and supported by the clips which attach the bar 5 to the switch 15 points. The bolts which fasten the bar 5 to said clips also extend through the trip bar 24 which is slotted where the bolts pass therethrough to allow said switch bar to have a limited sliding movement on the bar 20 5. At its inner end the trip bar 24 has arranged therein a bolt 25 which projects upwardly through a slot 26 in this end of the bar 5 and to the upper and lower ends of said bolt are secured a bail 27, the ends of 25 which engage the outer sides of the bars 5 and 24 and hold this end of the same in closed engagement. To the bolt 25 or to the bail 27 is secured the end of the operating rod 28 which connects the bar 5 with 30 the disk 9 of the switch throwing mechanism in the usual manner. Secured to the lower side of the trip bar 24 adjacent to the roller 23 on the arm 22 of the locking bar is a trip block 29, said block having a beveled or inclined end which when the trip bar and the 35 switch shifting bar are actuated by the switch throwing mechanism, engages the roller 23 on the arm 22 and forces the latter downwardly which operation also swings the free end of the locking bar 16 downwardly, 40 thus disengaging the notch in said bar from the rail 1 and switch tongue 3, whereupon the latter is released, so that a further movement of the bars 5 and 24 by the switch 45 throwing mechanism will open the switch point 3. It will be noted that by providing the switch shifting bar 5 with the slot 26 through which the bolt 27 projects and by providing the trip bar 24 with the slots 50 through which the clip attaching bolts pass that when the switch shifting mechanism is actuated to open the switch, the trip bar 24 is shifted for a short distance independently of the bar 5 or before the latter begins to 55 move. This preliminary independent movement of the trip bar 24 causes the trip block 29 to engage the roller 23 on the arm 22 and to thus depress the locking bar 16 a sufficient distance for disengaging the notch 18 therein 60 from the switch point 3 before the latter is shifted by the bar 5 thus preventing the locking bar from interfering with the free movement of the switch tongue by the switch throwing mechanism.

65 When the switch throwing mechanism is

actuated in the reverse direction and the switch tongue 3 thereby brought to a closed position the block 29 will be retracted from above the roller or sleeve 23 which will permit the spring 21 to force the locking bar 70 upwardly and thereby engage the locking notch therein with the switch tongue and track rail thereby locking the switch tongue in a closed position.

From the foregoing description taken in 75 connection with the accompanying drawings, the construction and operation of the invention will be readily understood without requiring a more extended explanation.

Various changes in the form, proportion, 80 and the minor details of construction may be resorted to without departing from the principle or sacrificing any of the advantages of the invention as claimed.

Having thus described my invention, what 85 I claim is:

1. In a switch locking device, the combination with the main track rails and a switch point, of a switch throwing mechanism comprising a point shifting bar connected to said switch point, said bar having near one end a longitudinal slot, a trip bar carried by and having a limited sliding movement on said point shifting bar, tripping means carried by said trip bar, a yielding supported locking bar having therein a notch adapted to engage one of the track rails and the switch point whereby the latter is locked in closed position and means carried by said locking bar and adapted to 100 be engaged by said tripping means whereby the locking bar is disengaged from said track rail and switch point prior to the movement of the latter by said shifting bar.

2. In a switch locking device, the combination with the main track rails and a switch point, of a switch throwing mechanism comprising a point shifting bar secured to said switch point, the latter having near one end a longitudinal slot, a trip bar 110 carried by and having a limited sliding movement on said point shifting bar, tripping means carried by said trip bar, a yielding supported locking bar having therein a notch adapted to engage one of the track rails and the adjacent switch point whereby the latter is locked in closed position and a laterally projecting member carried by said locking bar and adapted to be engaged by said tripping means whereby the locking bar 115 is disengaged from said track rail and switch point prior to the movement of the latter by said shifting bar.

3. In a railway switch lock the combination with the main track rails and switch 125 point of a switch throwing mechanism comprising a point shifting rod secured to the switch points, a locking bar having a notch adapted to engage one of the switch points and the adjacent rail and to thereby lock 130

the switch in a closed position, means to automatically project and hold said locking bar in an operative position, and means carried by said point shifting bar to disengage said locking bar from said switch point and 5 rail when said switch throwing mechanism is actuated.

4. In a switch locking device, the combination with the main track rails and switch points of a railway, of a switch 10 throwing mechanism comprising a point shifting bar secured to said switch points and having near one end a longitudinal slot, a trip bar carried by and having a limited sliding movement on said point shifting bar, 15 a trip block carried by said trip bar and having one end beveled, a locking bar pivotally supported at one end and having therein a notch adapted to engage one of the track rails and the adjacent switch point 20 whereby the latter is locked in a closed position, a spring engaged with the free end of 25 said locking bar whereby the latter is projected to and yieldingly held in an operative position, and means carried by said locking bar and adapted to be engaged by the trip block on said trip bar whereby the locking bar is disengaged from said track rail and switch point prior to the movement of the latter by said shifting bar.

30 5. In a switch locking device, the com-

bination with the main track rails and switch points of a railway, of a switch throwing mechanism comprising a point shifting bar secured to said switch points and having 35 near one end a longitudinal slot, a trip bar carried by and having a limited sliding movement on said point shifting bar, a trip block carried by said trip bar and having one end beveled, a locking bar pivotally 40 supported at one end and having therein a notch adapted to engage one of the track rails and the adjacent switch point whereby the latter is locked in a closed position, a spring engaged with the free end of said 45 locking bar whereby the latter is projected to and yieldingly held in an operative position, a roller carried by said locking bar and adapted to be engaged by the trip block of said trip bar when the latter is shifted by 50 said switch throwing mechanism thereby disengaging said locking bar from the rail and switch point prior to the movement of the latter by said switch throwing mechanism. 55

In testimony whereof I have hereunto set my hand in presence of two subscribing witnesses.

ORVILLE NELL.
